UNITED STATES PATENT OFFICE

GAIL D. BEAVER, OF NORRISTOWN, PENNSYLVANIA

CHUTE DISCHARGE UNIT

Application filed November 22, 1930. Serial No. 497,387.

My invention relates to the boot and boot casing of a chute for linen or the like, with particular reference to the support of the casing.

5 A purpose of my invention is to provide the upper section of a boot casing of the character indicated with a support from above as distinguished from a support from below.

10 A further purpose is to provide a boot casing of the character indicated with a three-point support; one at each side from above near its upper end, and one at the middle from below on the lower and more 15 forward section of the boot casing.

Further purposes will appear in the specification and in the claims.

I have elected to show one only of the many different forms of my invention, selecting a 20 form that is practical and efficient in operation and which well illustrates the principles involved.

Figure 1 is a fragmentary side elevation illustrating structure embodying one form of 25 my invention.

Figure 2 is a left side elevation of structure shown in Figure 1.

Like numerals refer to like parts in both figures.

30 Describing in illustration and not in limitation and referring to the drawings:—

My invention is believed to find its best application with linen chutes, such as are used in multi-story buildings, the chute often 35 running from the top floor to the basement with inlets at the individual floors and an elbow outlet, technically known as a boot, in the basement supported within and by a boot casing that is to be desirably supported by 40 mechanism embodying my invention.

The chute proper 6 is made of thin sheet material, preferably aluminum or other metal unable to stain linen passing down the chute, the lower end of the vertical body 6 fitting inside the upper and vertical inlet-section 7 of the three-section boot 8 which has a lateral outlet at 9 normally closed by a suitable door 10.

50 The boot comprises a three-section elbow with the upper and lower sections 7 and 11

respectively vertical and horizontal and the intermediate section 12 having a forty-five degree slope.

The boot will normally be of the same material as the chute body, usually aluminum 55 or an aluminum alloy, and of gauge too light to permanently withstand the often repeated sudden shock stresses incident to dropping linen or the like down the chute and having it strike the upwardly directed inclined inner 60 surface of the boot section 12.

The boot is protected and supported by a casing 13 that includes the non-vertical sections 11 and 12 of the boot and is divided at 14 along horizontally opposite sides, the 65 upper and lower divisions of the boot casing being fastened together after installation along mating flanges at 14, as by riveting, bolting or welding.

I show a drain pipe flange 15 on the bottom of the casing, a little rearward of the door, the boot being provided with a corresponding drain connection into a drain pipe carried by the flange 15.

The upper end of the upper boot section 75 receives the downwardly directed end of the body 6. Relatively heavy brackets 16, desirably steel and riveted to the chute section at circumferential intervals, each present a top horizontal face to a mating bottom 80 face of a corresponding bracket 17 of the main chute 6.

The horizontal top faces of the heavy brackets 16 are preferably even with the top edge of the boot section, the inner ends of 85 the rivets 18 that hold the brackets to the boot section 7 being covered when in place by the downward overlap of the chute section 6.

The brackets 17 of the upper section are 90 preferably of the same material as the body of the chute, as light sheet aluminum, with their upwardly extending vertical portions desirably welded to the body of the chute.

The outwardly extending portions of the 95 light brackets 17 rest on the horizontal faces of the heavy brackets 16 being clamped between the upper faces of the heavy brackets 16 and relatively heavy plates 19 by suitable bolts 20.

The bottoms of the light brackets form stops that limit and register the overlap between the chute body and the boot section 7.

I provide the boot casing with a three-point support, from above at points on substantially opposite sides of the vertical center line of the chute at 21 and 22 and from below at 23 directly under the middle of the boot casing toward the rearward end of the horizontal section of the casing, that is near the lower end of the intermediate sloping section, and preferably vertically below the main chute 6 near the forward side thereof.

I find that this type of support is particularly effective in preventing strains incident to use.

The lateral hanger rods 24 and 25 make adjustable connection at the bottom with lateral ears from the boot casing at the points 20 21 and 22, these ears being integral with or rigidly connected to the lower division of the casing.

The hangers 24 and 25 are supported at their upper ends upon suitable supporting structure 26 that may form part of or be carried by the superstructure of the building.

The divided casing may be made of sheet steel, the ear brackets at 21 and 22 being welded or otherwise fastened to the upper 30 end of the lower half of the casing on opposite sides of the center line of the body of the chute.

The support 27 from below is desirably a structural member such as a channel, bolted at the top to a suitable downwardly extending bracket 28 welded or otherwise connected to the casing and fastened at the bottom as at 29 to a suitable concrete foundation.

In view of my invention and disclosure 40 variations and modifications to meet individual whim or particular need will doubtless become evident to others skilled in the art, to obtain all or part of the benefits of my invention without copying the structure 45 shown, and I, therefore, claim all such in so far as they fall within the reasonable spirit and scope of my invention.

Having thus described my invention, what I claim as new and desire to secure by Letters Patent is:—

1. In chute mechanism of the character indicated, a boot, a casing about a lower and forward portion thereof and a three-point support for the casing including a support from above on each side of the casing and a support from below, said points being located so that the median point of a triangle having said points as apices will be on a vertical line well within the contour of the main vertical chute.

2. In chute mechanism of the character indicated, a boot, a casing about a lower and forward portion thereof and a three-point support for the casing including a support 65 from above on each side of the casing and a

support from below, said support from below being on a vertical line within the horizontal section of the main vertical chute and the supports from above being at opposite ends of a line within a vertical plane cutting the main chute longitudinally and spaced horizontally from the point of support from below.

3. In chute mechanism of the character indicated, a boot, a boot casing about a lower portion thereof and a three-point support for the casing including a support from above on each side of the casing and a support from below, said support from above being from points on substantially opposite sides of the center line of the chute and the support from below from a point below the main chute section near the forward side thereof.

4. In chute mechanism of the character indicated, a boot including a vertical inlet section, an intermediate sloping section and a horizontal outlet section, a boot casing about the intermediate and outlet sections and a three-point support for the casing including a support from above on each side of the casing on substantially opposite sides of the vertical center line of the chute and a support from below under the outlet section of the chute.

5. In chute mechanism of the character indicated, a boot, a divided boot casing having a lower division separated from an upper division along lines at substantially horizontally opposite sides of the casing and a three-point support for the said lower division including a support from above on each side of the casing and a support from below, said supports from above being from points on substantially opposite sides of the vertical center line of the chute and the support from below from a point below the main chute section near the forward side thereof.

6. In chute mechanism of the character indicated, a vertical chute body of light sheet aluminum having a downwardly directed end, outwardly extending light sheet ears welded thereto at intervals around the circumference near and spaced from the bottom edge thereof, an aluminum boot having a vertical end fitting around the lower end of the body, heavy brackets on the inlet end of the boot under the ears, means clamping the ears to the brackets, a boot casing about the lower and forward portion of the boot and a three-point support thereof including a support from above on horizontally opposite sides of the casing and a support from below spaced forwardly from the supports from above.

GAIL D. BEAVER.
